UNITED STATES PATENT OFFICE

95,605

DESIGN FOR KNIT FABRIC

William Avery Neaves, Elkin, N. C., assignor to
Chatham Manufacturing Company, Winston-
Salem, N. C., a corporation of North Carolina

Application January 21, 1935, Serial No. 54,983

Term of patent 7 years

To all whom it may concern:

Be it known that I, William Avery Neaves, a citizen of the United States, residing at Elkin, in the county of Surry and State of North Carolina, have invented a new, original, and ornamental Design for Knit Fabric, of which the following is a specification, reference being had to the accompanying drawing, forming part thereof.

Figure 1 is a plan view of a portion of a knit fabric embodying the design; and

Figure 2 is a jogged section taken along the line 2—2 of Figure 1.

In the drawing, the groups *a* of three stitches

and the stitches *1* and *2* of the alternate groups *b* are elevated and in a common plane. The side stitches *3* and *4* of the groups *b* are depressed, giving the groups *b* a convex appearance as contrasted with the flat groups *a*.

The groups *c* and *d* of two stitches are alternately elevated and depressed, the elevated groups *c* being in the same plane as the groups *a* of three stitches.

I claim:

The ornamental design for a knit fabric as shown and described.

WILLIAM AVERY NEAVES.
